US00D851039S

(12) **United States Design Patent** (10) **Patent No.:** **US D851,039 S**
(45) **Date of Patent:** **** Jun. 11, 2019**

(54) **ACCUMULATOR**

(71) Applicant: **Robert Bosch GmbH**, Stuttgart (DE)

(72) Inventor: **Christoph Schumacher**, Dusslingen (DE)

(73) Assignee: **Robert Bosch GmbH**, Stuttgart (DE)

(**) Term: **15 Years**

(21) Appl. No.: **29/623,881**

(22) Filed: **Oct. 27, 2017**

(30) **Foreign Application Priority Data**

Apr. 27, 2017 (EM) 003874940

(51) **LOC (11) Cl.** **13-02**

(52) **U.S. Cl.**

USPC **D13/110; D13/104**

(57) **CLAIM**

The ornamental design for an accumulator, as shown and described.

DESCRIPTION

Cross reference is made to copending U.S. design patent application Ser. No. 29/576,267 entitled "Accumulator" by Greiner, Rinaldo, which was filed on Sep. 1, 2016 now D756,920; U.S. design patent application Ser. No. 29/576,271 entitled "Accumulator" by Greiner, Rinaldo, which was filed on Sep. 1, 2016 now D826,846; U.S. design patent application Ser. No. 29/623,868 entitled "Accumulator" by Schumacher, Christoph, which was filed on even date here-with; U.S. design patent application Ser. No. 29/623,876 entitled "Accumulator" by Schumacher, Christoph, which was filed on even date here-with; and U.S. design patent application Ser. No. 29/623,892 entitled "Accumulator" by Schumacher, Christoph, which was filed on even date here-with.

FIG. 1 is a perspective view of an accumulator showing my new design;

FIG. 2 is a right side elevational view of the accumulator of FIG. 1;

FIG. 3 is a left side elevational view of the accumulator of FIG. 1;

FIG. 4 is a top plan view of the accumulator of FIG. 1;

FIG. 5 is a bottom plan view of the accumulator of FIG. 1;

FIG. 6 is a front elevational view of the accumulator of FIG. 1; and,

FIG. 7 is a rear elevational view of the accumulator of FIG. 1.

The broken lines shown in the drawings illustrate portions of the accumulator that form no part of the claimed design.

1 Claim, 4 Drawing Sheets
